ABSTRACT OF THE DISCLOSURE

The invention relates to a clock driven by a synchronous electric motor and adapted to be reset at periodic intervals from signals received from a master clock. The clock forming the subject matter of this invention is provided with means for inhibiting or preventing a reset signal from causing reset action to occur if the clock is on time. If reset is called for, then such action takes place over an appropriate time interval. The particular invention involved here relates to the mechanical structure between armature normally responsive to signal reset impulses and a generally conventional reset mechanism. This conventional reset mechanism has been modified to embody the reset inhibiting function. In addition, the cam arrangement provides for more accurate control.

This invention relates to a clock mechanism and more particularly to a clock powered by a synchronous electric motor and having means for reset in response to suitable signals from a master station. The invention is characterized by reset prevention when unnecessary because the clock is on time.

In my prior application S.N. 694,946 filed Jan. 2, 1968, I have disclosed and claimed such clock operation. The present invention is an improvement upon the clock disclosed in my prior application. The improvement disclosed herein effects some economies in engineering and tooling.

The details of the present invention can best be understood by reference to the drawings taken in conjunction with the description which follows.

Referring now to the drawings: FIG. 1 shows a side elevation of the clock embodying the present invention.

FIG. 1-A is an exploded perspective view of the parts of a stop disc assembly, forming part of the clock mechanism.

FIG. 1-B shows a side view of one side of a stop disc. FIG. 1-C shows the other side of a stop disc.

FIG. 1-D is an edge view of the stop disc.

FIG. 2 is an exploded perspective view of the clock shown in FIG. 1, certain parts being omitted for clarity and the relative positions of the parts being distorted for ease of illustration.

FIG. 2-A is a detail of the armature locking portion thereof.

FIG. 3 is an enlarged partial view in elevation of certain details of the clock, illustrating cams and cam-follower and armature locking means, this figure showing the clock mechanism in normal condition where no reset is called for.

FIG. 4 is a view generally similar to FIG. 3 showing reset blocking position of parts and also showing parts broken away to illustrate clock reset action.

FIG. 4-A is a detail illustrating parts of the reset mechanism of the lower right hand portion of FIG. 4.

The clock parts are supported in a structure having front plate 5, middle plate 6 and rear plate 7 disposed in laterally offset parallel spaced planes. The plates are of steel, brass, or any other material strong enough to support the component parts in conventional fashion in

2

the clock art. The three plates are maintained in fixed relative position by spacing sleeves 8 and screws 9. As is usual in the clock art, stamped gears having metal cutouts therefrom to reduce weight are carried on spindles.

Secured to the outer face of rear plate 7 is synchronous motor 10 driving pinion 12. Between the motor proper and pinion 12, there may be a gear-train for reducing the speed of the motor shaft so that pinion 12 will turn at 1 r.p.m. as an example. Rear plate 7 is apertured to permit pinion 12 to project into the space between middle plate 6 and rear plate 7. Pinion 12 is connected through friction coupling 12a to seconds arbor 14. Arbor 14 extends through front plate 5 and normally carries a seconds indicating hand, not shown, for conventional clock display. Inasmuch as friction couplings are well known in the clock art, no detailed showing is necessary.

Firmly secured to the coupling portion for seconds arbor 14 is stop arm 14a. Stop arm 14a will turn with seconds arbor 14 and, as will be explained later, is used to stop rotation of the seconds arbor. Further along on seconds arbor 14 in the direction of clock drive toward front plate 5 is pinion 14e which meshes with reducing gear 14f carried on a small spindle laterally offset from the axis of seconds arbor 14. Reducing gear 14f drives small gear 14g on the same spindle, and this small gear in turn drives minute drive gear 14h. Minute drive gear 14h is concentric with seconds arbor 14 and is coupled through friction clutch 14i to minute tube 14j, which extends through front plate 5. Secured to minute tube 14j is first minute drive pinion 14k which meshes with intermediate gear 14m. This intermediate gear 14m comes into play in connection with reset action of mechanism to be described later.

Returning to minute drive gear 14h, as noted earlier, this drives minute tube 14j carrying a pair of cams 14p and 14q. Cam 14p is a minute lockout cam while cam 14q is a "twelve hour" timer cam. Both of these cams are rigidly secured to minute tube 14j, and their cam shapes and functions will be described later. Also secured to 14j is an additional minute drive pinion 14r, which meshes with minute tube hour reduction gear 14s, which carries pinion 14t on the same spindle. Gears 14s and 14t are carried on a spindle offset from the axis of seconds arbor 14a. Gear 14t drives hour gear 14v secured to hour tube 14w.

Hour tube 14w has secured thereto "twelve hour" lockout cam 14u. With the exception of intermediate reset gear 14m, the various parts carrying numeral 14 and letters from 14e through 14w are used in connection with conventional clock drive for time keeping purposes.

For reset, pinion 12 from motor 10 meshes with gear 15 to provide an alternate path for power flow to minute pinion 14k. Gear 15 meshes with gear 15a, secured to spindle 15A and also secured to ratchet gear 15B. Spindle 15A passes through sleeve 16a of a stop-disc assembly 16. Stop-disc assembly 16 has disc 17 carrying pick-up pawl 17c. Pivot 17b for pick-up pawl 17c is displaced from the center of disc 17. Disc 17 carries stop pin 17a near the edge thereof to limit the rocking of pick-up pawl 17c. Pick-up pawl 17c has at one end thereof claw 17d extending laterally from the face of disc 17 and is normally adapted to override the teeth of ratchet gear 15b. Pick-up pawl 17c is biased so that claw 17d normally tends to engage a tooth of ratchet gear 15B. This bias is provided by small spring 17e pressing against one tip 17f of pick-up pawl 17c. Spring 17e extends through slot 16b in disc 17, and forms a part of a spring metal secured to disc 17. Pickup pawl 17c also has detent finger 17g which extends beyond the edge of disc 17. Sleeve 16a extends through disc 17 beyond the other side of the disc from the side carrying pick-up pawl 17c. On this other side of disc 17 metal pick-up spring finger

17m is rigidly secured to disc 17 at 17p, and forms part of the S-shaped piece of spring metal secured to disc 17 at sleeve 16a carrying previously mentioned spring 17e. Spring finger 17m is shaped as an arcuate strip sprung laterally away from disc 17 toward disc 18 and terminating in sharp tip 17q.

Disc 18 has sleeve portion 18a which is adapted to slide over sleeve portion 16a of disc 17. Disc 18 is disposed against that face of disc 17 carrying arcuate spring finger 17m. Disc 18 has radial slot 18b extending from the edge of the disc having slot sidewalls 18c and 18d. As seen from front plate 5, ratchet gear 15B normally rotates in a clock-wise direction and when claw 17d engages a tooth of the ratchet gear during reset, stop-disc 17 will be driven in a clock-wise direction. It is understood that the ratchet teeth of 15B are shaped so that such engagement between the claw and teeth of the ratchet gear is possible. When reset is occurring, disc 18 is also driven in a clock-wise direction as viewed from front plate 5. Side wall 18c of disc slot 18b will be the leading side when disc 18 is driven from ratchet gear 15B. This leading side wall 18c is bent laterally toward disc 17 so that sharp end 17q will catch against laterally offset slot wall 18c after disc 17 has turned and spring finger 17m passes slot wall 18d and encounters slot 18b. Thus between disc 17 and disc 18 there is effectively provided a one way drive in appropriate direction for transmitting reset power from ratchet gear 15B to disc 18. Between disc 15B and disc 17 there is provided what in effect is a fast acting clutch.

Sleeve 18a, secured to disc 18 carries reset pinion 18g which meshes with intermediate reset gear 14m. As heretofore described, intermediate gear 14m meshes with minute gear 14k and thus, when reset is occurring, functions to turn reset gear 14k and minute tube 14j at an accelerated rate in a clock-wise direction for reset action. As will be shown later, a complete operating reset cycle is initiated when claw 17d engages a tooth of ratchet gear 15B and causes rotation of disc 17 from a predetermined starting position through a complete turn to the stopping position, which becomes the starting position for a succeeding reset cycle. Gear ratios for reset are such that during a reset cycle (which is initiated only by a signal pulse) reset advances the entire clock mechanism by almost an hour (as for example 58 minutes) depending on the operating characteristics of the clock system.

Referring to cams 14p and 14q, each such cam has its own individual follower p and q. These two followers are essentially similar and are rockable about stationary pivot pin p1. Follower p has lateral extension p2 to which is attached one end of coil spring p3 the other end of which is anchored to fixed pin p5. The arrangement is such that coil spring p3 will bias follower p so that cam follower tip p7 presses against the edge of cam 14p. The outer edge of cam 14p functions as a cam surface and is provided with a drop subtending a prescribed angle corresponding to several minutes of clock time in accordance with the rotation of minute tube 14j. The shape of the cam drop is such that follower p drops suddenly at the leading edge of the cam drop and can rise slowly at the trailing end. This particular action of follower p in cooperation with cam 14p is more fully described in my aforementioned patent application.

Follower p has its free end p8 rounded to bear against plate pq, forming part of lockout lever pq1 pivoted for rocking about pin pq2. When pointed tip p7 goes into the drop of cam 14p, due to the pull of bias spring p3, follower p will rock clockwise, as seen from front plate 5, and will rock lockout lever pq1 clockwise until pq rests against stop pin pq4 carried by plate 6. Lockout lever pq1 is long enough so that it can cover part of slot 6a in the edge of middle plate 6 when rocked. Normally lockout lever pq1 is weakly biased by spring pq3 to be below slot 6a. In such a condition, follower p is in its

normal counterclockwise position with tip p8 in its up position. Spring pq3 is much stronger than spring pq3.

Cam follower q is similar in all respects to follower p with corresponding parts carrying corresponding numbers. Cam 14q has a cam drop which is much greater in angular extent than cam p. Both cams have aligned leading sharp drops. However cam 14q has its drop great enough so that its follower can remain down for about twenty minutes, as an example, in the signal pattern used at the master clock, as more fully described in my earlier application.

Hour cam 14u has its follower u rockable about pin p1 and is tied by pin qu to follower q to rock together. Cam 14q functions as a supplement to cam 14u to provide accuracy at the ends of the cam drop for hour cam 14u.

The arrangement is such that lockout lever pq1 will be rocked to cover slot 6a when any one or more of cam followers p, q and u are in a cam drop. Otherwise lockout 20 lever pq1 will be biased by its spring pq3 so that slot 6a is not covered.

Disposed in slot 6a is the end part of arm 6b extending laterally through plate 6 toward rear plate 7 and forming part of actuator trip slide 6c. Slide 6c lies 25 against the inner surface of rear plate 7 and extends toward the edge of rear plate 7 adjacent to stop disc assembly 16 previously described. Actuator trip slide 6c is maintained in position against the inner face of rear plate 7 by rivets carrying enlarged heads, the rivets 30 being in long slots 6d for permitting slide 6c to move longitudinally over a limited distance. Actuator trip slide 6c has its end 6e apertured to accommodate finger 6e' extending from armature 6f.

Armature 6f has pivot points 6g for mounting on a 35 ferro-magnetic bracket secured to rear plate 7. Armature 6f has extension 6i to which bias spring 6j has one end attached, the other spring end being attached to the bracket. Thus armature 6f is normally biased away from the free core end of the electromagnet. When winding 40 6m is energized from the master clock, armature 6f is attracted and associated arm 6b tends to move deeper into slot 6a.

If armature 6b is free to move deeper into slot 6a, actuator trip slide 6c is moved longitudinally toward 45 the right as viewed from front plate 5. If lockout lever pq1 covers part of slot 6a, then armature response to winding energization is prevented.

The mechanism so far described can function to block armature response when no reset is called for. When 50 reset is called, the armature is free to respond to the energization of the electromagnet (due to the fact that the clock is off-time) the following additional mechanism is provided and will come into play. Actuator trip slide 6c has its free end rounded and normally rests near 55 pick-up pawl throwout lever 20, which extends generally perpendicular to the planes of the clock plates and for most of the distance between middle plate 6 and rear plate 7. Pick-up pawl throwout lever 20 is irregularly shaped and has body portion 20a and bent end portion 60 20b with downwardly extending support portion 20c pivotally carried by pin 20d on plate 6. Pick-up pawl throwout lever 20 is normally biased to an idle position by spring 20e extending between tail piece 20f and stationary anchor pin 20g secured to middle plate 6. Body 65 portion 20a normally functions as a detent against tip 17g of pick-up pawl 17c to keep claw 17d clear of the teeth of ratchet gear 15B. When actuator trip slide 6c is moved longitudinally for reset, pick-up pawl throwout lever 20 is rocked slightly in a clock-wise direction 70 sufficiently to clear tip 17g of the pick-up pawl and permit engagement to take place between ratchet gear 15B and stop disc 17 as previously explained.

Stop disc 17 is provided with peripheral notch 17k into which tip 21a of aligner lever 21 normally rests. Lever 21 is pivotally secured at pin 21b carried by plates

6 and 7. Lever 21 has extension arm 21c whose free end is normally outside the orbit of second stop finger 14a. Lever 21 and its extension arm 21c is biased by spring 21d extending between arm portion 21c and pin 21e carried by plate 6. Lever 21 is biased so that tip 21a will be pressed against the edge of stop-disc 17. During reset when stop-disc 17 begins to turn in a clock-wise direction, as seen from the front of the clock, tip 21a of lever 21 will be forced out of notch 17k in disc 17 and will rock lever 21 and its extension arm 21c so that the extension arm is moved into the orbit of seconds stop finger 14a. Extension arm 21c will stop clock-wise rotation of that portion of the clutch on seconds arbor 14 and stop clock drive through the seconds arbor. It should be noted however that motor pinion 12 is still turning and will drive gear 15 for reset.

Once reset action is initiated, reset goes through one cycle which causes stop-disc 17 to make a complete revolution. Reset will be terminated when disc 17 has positioned notch 17k allowing tip 21a to drop. It is understood that if the duration of a reset signal is longer than reset then a second reset cycle may be initiated. However, in practice, the various gear ratios are so arranged that a complete reset cycle will take one minute, whereas a signal will run no more than 57 seconds and will not be repeated until after an entire minute has passed from the end of a reset cycle.

Aligner lever 21 carries pin 21k which extends laterally toward middle plate 6 and is caught in slot 22a of throw-out lever 22. This throwout lever is pivoted at pin 22b an has its edge so positioned as to permit an end of side portion 20b of the pick-up pawl throwout lever 20 to rest against the same. The relationship between throwout lever 22 and pick-up pawl throwout lever 20 is such that once stop-disc 17 has started to turn during reset, throwout lever 22 will keep body portion 20a clear of throwout pawl 17c and prevent any possibility of claw 17d from disengaging from the tooth of ratchet gear 15B during a reset cycle.

The arrangement of the various members is such that when the armature does move in response to a call for reset, seconds arbor 14 is stopped in a predetermined position (such as twelve o'clock), reset begins and minute tube 14j is turned clockwise until the predetermined minute position is reached. At the end of a reset cycle, the seconds arbor and minute tube can both start from the predetermined position. If the clock is off for several hours, reset will be called for by successive signal pulses until the clock is fully reset. A complete reset action is fully described in my previously identified earlier patent application.

The general construction of means for providing reset including a ratchet gear which is continuously driven from the electric motor drive in the clock and having a pick-up pawl which is normally free of the teeth of the ratchet gear and having a pawl throwout lever for permitting said pawl to engage a tooth of the ratchet gear is old and well known; similarly a stop disc assembly carrying the pick-up pawl and having a one way drive for connecting the pick-up gear through the stop-disc assembly to a gear for driving a minute gear for reset and controlled by a one revolution clutch, together with means for stopping rotation of the seconds arbor are also old as for example in U.S. Pat. No. 2,569,815 issued Oct. 2, 1951 to Larrabee.

The operation of the clock, both during reset and when reset is blocked, has been fully set forth.

What is claimed is:

1. A remote clock comprising a plurality of laterally offset spaced parallel plates, means for maintaining said plates in fixed positions; a seconds arbor, a minute tube about said arbor, an hour tube about said minute tube, means for supporting said arbor and tubes in said plates for rotation; a synchronous motor drive pinion, means including a friction clutch for connecting said motor drive

pinion to said seconds arbor to drive the same; a gear train connecting said seconds arbor and a minute drive gear, a friction clutch between said minute drive gear and the minute tube, at least one minute cam coupled to said minute tube to rotate in fixed relation thereto; a gear train between said minute tube and hour tube, an hour cam coupled to said hour tube to rotate in fixed relation thereto; a clock reset power drive including a gear train between said motor drive pinion and minute tube for driving said minute tube at an accelerated rate for reset, said reset power drive including a ratchet gear and a stop disc coaxial with said ratchet gear but independently rotatable and normally stationary; a pick-up pawl carried by said stop disc and rockable about an axis parallel to and laterally offset from the stop disc axis, said pick-up pawl having a claw portion overriding the ratchet gear teeth and rockable to engage or clear ratchet teeth; spring means biasing said pawl into ratchet gear tooth engaging position, a pawl throw-out lever engageable with said pawl for retaining said pawl in an idle position; a one way drive between said stop disc and minute tube in a direction for reset; a stop finger on said seconds arbor; a follower for each cam, each cam having a portion thereof shaped to move its follower from a clock reset calling position to a reset blocking position; electromagnetic means including a winding and movable armature, said winding being adapted to receive reset signal pulses from a master clock at predetermined times; means for biasing said armature to a normally inactive position from which position winding energization tends to move said armature to a clock reset calling position; detent means disposed between said cam followers and armature for preventing armature movement from its normally inactive position when the clock is on time with both minute and hour cams oriented so that their followers are in reset blocking position; actuating means disposed between said armature and pawl throwout lever and responsive to armature movement for releasing said pick-up pawl to respond to its bias and establish a driving connection between the ratchet gear and said stop disc and initiate a minute gear reset cycle; a rockable lever having one end as a cam follower for cooperation with said stop disc and having its other end as a detent finger, said rockable lever normally being in a stand-by position when no reset action is occurring and with its detent finger inactive; said stop disc, upon rotation at reset initiation, rocking said rockable lever to move the detent finger into the orbit of said seconds arbor stop finger to stop rotation of said seconds arbor; said stop disc, at the end of its revolution, moving said rockable lever to its normal stand-by position and said pawl throwout lever engaging said pawl to maintain the pawl in an idle position; said reset cycle being reinitiated by a succeeding reset signal pulse so long as reset is called for.

2. The construction according to claim 1 wherein an additional minute cam is provided, the two minute cams being in aligned relation, one minute cam having a cam drop whose angular extent is sufficient to accommodate one reset cycle in response to a reset signal, said other minute cam having a cam drop whose angular extent is substantially greater than that of the first cam and can accommodate a number of successive reset cycles each of which is initiated in response to a reset signal, said two cams having their leading edges aligned and shaped to provide a quick drop for each cam follower and a generally gradual rise for the trailing end of each cam drop, said hour cam also having a drop whose angular extent is great enough to accommodate the longest reset calling drop of said other cam on the minute arbor, said hour cam having its leading cam drop edge aligned with the two minute cams, said other minute cam supplementing the action of said hour cam for precision control, means for tying the follower for the other minute cam and the follower for the hour cam to rise or drop simultaneously, all of said cam drops corresponding in time, when a clock

is running on time, to periods for reset signal reception, said reset blocking action occurring normally when a cam follower is at a cam drop with the clock running on time.

3. A construction according to claim 1 wherein said detent means includes a lock-out lever rockable about a pivot point, means coupling each of said cam followers to one portion of said lock-out lever, an armature actuated member movable in a slot in a plate of said clock, said lock-out lever being movable from a position where it clears a portion of said slot to a reset blocking position where it covers a portion of said slot, means for supporting said armature actuated member and said lockout lever so that when the latter covers part of said slot, it

prevents movement of said member and thus prevents armature response to signal energization of the winding.
